DISPENSING DEVICE

Leo M. Harvey, Los Angeles, Calif.

Application September 12, 1938, Serial No. 229,446

10 Claims. (Cl. 312—51)

This invention relates to a dispensing device and relates more particularly to a device for dispensing paper towels and similar sheet material articles. A general object of this invention is to provide a simple, practical and economical device for dispensing paper towels and the like.

The persons operating the paper towel dispensing devices in public lavatories, etc. usually have wet hands when they engage the towels to withdraw them from the cabinets. The moisture on the hands is transferred to and absorbed by the portion of the towel grasped by the user and often softens and weakens the towel. In many instances the softened towel tears or parts in the user's hands before he is able to withdraw the towel from the cabinet, and considerable difficulty is sometimes encountered in obtaining the torn or parted towel.

An important object of this invention is to provide a towel dispensing device that ejects a folded or double-thickness part of the towel that may be grasped and pulled by wet hands without failing, parting or tearing. The folded double-thickness portion of the towel ejected from the device of the present invention has sufficient strength to withstand a substantial pull and has increased water absorbing capabilities so that it does not part when grasped and pulled by wet hands.

Another object of this invention is to provide a dispensing device of the character referred to that is operable by a single, simple manipulation of one operating part to project or expel a portion of a towel or sheet material article for convenient engagement and removal by the user.

Another object of this invention is to provide a dispensing device that cannot be repeatedly operated in rapid succession to obtain a number of towels or sheet material articles.

Another object of this invention is to provide a dispensing device of the character mentioned that embodies a novel and effective retarding or time delay means associated with the ejecting mechanism to prevent the ejection of the towels or articles in rapid succession and thus prevent the needless and wasteful removal of a plurality of towels or articles. The users of towel cabinets provided in public lavatories, and the like, often operate the cabinets to obtain more towels than necessary and rapidly deplete the supplies of towels in the cabinets. The device of the present invention embodies a practical, dependable time delay means that makes it necessary

for the user to wait a given period between each towel ejecting operation, to deter the user from attempting to obtain more towels than actually required.

5 Another object of this invention is to provide a dispensing device of the character referred to in which the time delay means retards the return of the ejector during the second or final phase of its return stroke and allows the rapid and immediate return of the ejector through the first phase of its return stroke so that the ejector is immediately withdrawn and concealed within the device upon the completion of the ejecting stroke.

10 Another object of this invention is to provide a dispensing device of the character referred to in which the time delay means is adjustable or regulable to have the selected or required action.

15 Another object of this invention is to provide a towel cabinet or dispensing device of the character mentioned in which the operating member or handle is free of and disconnected from the ejecting mechanism during the retarded return stroke of the ejector, and is immediately returned independently of the ejecting mechanism.

20 Another object of this invention is to provide a towel cabinet or dispensing device of the character mentioned that embodies a novel and effective means for maintaining the sheet articles or towels centralized and in the correct relation for ejection by the ejecting mechanism.

25 Another object of this invention is to provide a dispensing device or towel cabinet in which the operating button or handle is automatically cleansed and wiped dry by the towel as the towel is withdrawn from the device, so that the handle is in a dry, sanitary condition at the termination of each operation of the device.

30 Another object of this invention is to provide a dispensing device or towel cabinet of the character referred to in which actuation of the handle prior to the return of the ejector to the end of its return stroke does not result in fouling of the towels, bending of the towels, partial ejection of the towels, or impairment of the ejecting mechanism.

35 Another object of this invention is to provide a dispensing device of the character mentioned in which the operator or user must complete the removal or withdrawal of the towel from the device to condition the device for further operation.

40 A further object of this invention is to pro-

vide a dispensing device of the character mentioned that is simple and inexpensive and that is compact and pleasing in appearance.

The various objects and features of my invention will be fully understood from the following detailed description of typical preferred forms and applications of the invention, throughout which description reference is made to the accompany drawings, in which:

Fig. 1 is a front view of the improved dispensing device provided by this invention. Fig. 2 is a side view of the device. Fig. 3 is an enlarged vertical detailed sectional view of the device illustrating the parts in the normal or unactuated positions and showing a portion of one side of the cabinet in elevation. Fig. 4 is an enlarged fragmentary horizontal detailed sectional view taken as indicated by line 4-4 on Fig. 3. Fig. 5 is an enlarged detailed sectional view taken as indicated by line 5-5 on Fig. 3 showing the wall of the cylinder broken away. Fig. 6 is an enlarged fragmentary vertical detailed sectional view of the lower portion of the device, illustrating the ejector in its fully actuated position. Fig. 7 is a view similar to Fig. 6 showing the towel being withdrawn from the cabinet and Fig. 8 is a fragmentary vertical detailed sectional view of a slightly modified form of the invention.

The embodiment of the invention illustrated in Figs. 1 to 7, inclusive, of the drawings, may be said to comprise, generally, a housing or cabinet 10 for containing a stack of folded sheet articles or towels T, an ejector 11 in the cabinet 10, means 12 for actuating the ejector 11 to eject the lowermost towel T for removal from the cabinet 10 and a control or time delay means 13 associated with the ejector 11.

The cabinet 10 is provided to contain the towels T and to house and support the various other parts of the device. The cabinet 10 may be varied considerably in construction and design without departing from the invention. In the embodiment of the invention illustrated in the drawings the cabinet 10 is formed of sheet metal or the like, and is adapted to be attached to a vertical support such as a wall, or the like. The cabinet 10 illustrated in the drawings includes spaced vertical sides 14, a back 15, a bottom 16, a top 17 and a hinged front 18. The top 17 may curve or slope downwardly and forwardly and the bottom 16 may be generally horizontal. The bottom 16 is bent or shaped to have a substantially vertical forwardly facing wall part 19 and a downwardly facing wall 20 extending forwardly from the part 19. An elongate opening 21 occurs immediately in front of the wall 20 to provide for the discharge of the towels T from the cabinet 10. The opening 21 faces downwardly and forwardly and is at the lower edge of the cabinet front 18.

The front 18 is hinged at its lower edge to be swung between the closed position illustrated in the drawings and an open position where the interior of the cabinet 10 is readily accessible. A hinge pin 22 serves to pivotally or hingedly support the front 18. The front 18 is adapted to engage rearwardly against the forward edges of the case sides 14 and its upper portion is curved to merge with the sloping top 17. A suitable lock 23 may be provided on the top 17 to retain the front 18 in its closed position. A mirror 24 may be provided on the front 18. The front 18 may be provided with rearwardly turned flanges 25 for overlapping the forward edge portions of the case sides 14. A viewing slot 26 may 75

be provided in one of the case sides 14. Substantially vertical mounting plates 37 are arranged in the lower portion of the housing or cabinet 10 to carry the ejecting mechanism, etc. 5 The plates 37 are adjacent the case sides 14 and may have flanges or lips 38 secured to the bottom 16.

The invention provides means for supporting the stack of towels T in the cabinet 10. This means includes a substantially horizontal shelf 27 arranged in the cabinet 10 at the inner surface of the front 18 and immediately above the discharge opening 21. A roll 28 is provided along the rear edge of the shelf 27 to assist in guiding the towels T through the opening 21. Parts of the shelf 27 may form the stationary cheeks of the hinge for the front 18. In the preferred construction the forward shelf 27 is quite narrow. As illustrated in the drawings the shelf 27 is engaged by the forward edge portion of the lowermost towel T to support the forward portion of the stack of towels. The towel supporting means further includes a rear shelf 29 for supporting the rear portion of the stack of towels. The shelf 29 extends between the plates 37 and may be supported on the upper edges of the spaced plates. Down-turned lips or flanges 30 on the shelf 29 may be received in notches in the plates 37 to hold the shelf in place. The forward major portion of the rear shelf 29 slopes downwardly and forwardly. The shelf 29 is spaced rearwardly some distance from the forward shelf 27 and means is provided between the two shelves to assist in supporting the stack of towels T. In the preferred construction this means comprises a horizontal rod or roller 31 extending across the interior of the cabinet 10 in spaced relation to the spaced shelves 27 and 29. The opposite end portions of the roller 31 are rotatably supported in openings 32 in the plates 37. The roller 31 is spaced some distance forwardly from the rear shelf 29 and lies in substantially the same horizontal plane as the forward shelf 27.

The sheet material articles or towels T are generally rectangular members folded to each have a front fold 33 and a rear fold 34. The folds 33 and 34 are folded back upon the under sides of the towels T and are of substantial width. The opposing inner edges of the folds 33 and 34 are spaced some distance apart. The towels T are arranged in corresponding positions in the cabinet 10 and are preferably substantially horizontal.

The invention provides novel and effective means for maintaining the towels T in the correct positions in the cabinet and for guiding the towels for ejection by the ejector 11. This means includes a vertically extending guide rib 35 on the inner surface of the case front 18. The rib 35 is U-shaped or V-shaped in horizontal cross section and is spaced midway between the opposite vertical edges of the front 18. The rib 35 extends from the curved upper portion of the front 18 to immediately adjacent the front shelf 27. Notches 39 are provided in the forward edges of the towels T to receive or cooperate with the rib 35. There is one notch 39 in the folded forward portion of each towel T and the notches 39 of the stacked towels register to form a vertical groove which receives the guide 35. The notches 39 are shaped so that the rear edge or rearmost surface of the rib 35 engages the walls of the notches 39. This engagement of the guide 35 in the notches 39 serves to maintain the towels T in their proper positions and

yet allows free vertical movement of the towels T. The towels T guided by the rib 35 do not drag or hang up on the case front 18 and are free to successively move downwardly for engagement by the ejector 11.

If desired or found necessary a weight or follower 40 may be arranged on the top of the stack of towels T. As illustrated in Fig. 3 of the drawings the forward edge portion of the lowermost towel T rests on the forward shelf 27 and the front fold 33 of the towel extends inwardly from the shelf 27 to hang free or depend in the open lower portion of the cabinet 10. The rear fold 34 of the lowermost towel T has a portion resting on the shelf 29 and its forward edge portion may hang substantially free. The intermediate part of the lowermost towel T between the folds 33 and 34 rests on the above described roller 31 and the roller serves to support the middle portion of the stack of towels T.

The ejector 11 is provided to engage with the front fold 33 of the lowermost towel T to bend or project the same forwardly through the opening 21 and thus make a double-thickness portion of the towel accessible for convenient engagement by the user. The ejector 11 is in the nature of a swinging or pivoted element housed in the lower forward portion of the cabinet 10. In the preferred construction the towel ejector 11 includes two sections or members 41 and 42. The member 41 may be a flat plate-like part and is disposed between the spaced mounting plates 37. The forward edge portion of the member 41 is rolled and secured to a shaft 43. Welding may secure the rolled forward edge portion of the member 41 to the shaft 43. The opposite end portions of the shaft 43 are rotatably carried by suitable bearings 44 on the mounting plates 37 and spacers 56 are provided on the shaft between the ejector 11 and the bearings 44. The ejector member 42 is a curved plate-like part hingedly connected with the member 41. The rear edge of the member 41 and the lower edge of the member 42 have intermeshing rolled parts 45 and a hinge pin 46 passes through the rolled parts 45 to hingedly or pivotally connect the two members 41 and 42. Torsional springs 47 are arranged around the pin 46 and cooperate with the two ejector members 41 and 42 to yieldingly urge the member 42 to pivot upwardly or rearwardly relative to the member 41. Stop lugs 48 are provided on the member 42 to cooperate with the member 41 and serve to limit the upward pivoting of the member 42 relative to the member 41.

The member 42 is curved in vertical cross section, curving upwardly and forwardly, assuming the ejector to be in the position illustrated in Fig. 3. A freely rotatable roller 49 is provided on the forward edge of the ejector member 42. The rear or upper surface of the member 42 is adapted to ride on or cooperate with the rotatable roller 31. When the ejector 11 is in its normal or retracted position the forward part of the ejector member 42 bears upwardly against the roller 31. The torsional springs 47 serve to maintain the member 42 in cooperation with the roller 31. Upon upward and forward pivoting of the ejector 11 the cooperation of the member 42 with the roller 31 cams or directs the member 42 forwardly through the opening 21. As the forward movement of the member 42 progresses the torsional springs 47 urge or pivot the member 42 upwardly relative to the member 41 and when the ejector 11 is in its fully

extended position the member 42 is raised to its maximum extent and the stop lugs 48 engage the member 41 to stop such pivoting. The engagement of the ejector member 42 with the roller 31 is such that the roller 49 may lightly ride on the under side of the lowermost towel T without raising, moving or disturbing the towel.

During the above described forward movement of the ejector 11 the roller 49 enters between the fold 33 and the under side of the lowermost towel T and as the ejector continues to move forwardly the roller 49 and the member 42 bend or move the fold 33 downwardly and outwardly through the opening 21 as illustrated in Fig. 6. The lowermost towel T remains engaged on the shelf 27 during this ejection of the fold 33. The lower side of the curved ejector member 42 moves in close relation to the lower wall of the opening 21 so that the fold 33 is confined against the wall. This prevents the fold 33 from straightening out and becoming disengaged from the roller 49 and the ejector member 42. The towel fold 33 engaged about the roller 49 and the member 42 and projecting from the opening 21 is conveniently engaged by the user of the device and may be pulled forwardly without parting or tearing. The user may readily grasp the projected towel fold 33 without contacting the cabinet 10 with his wet hands.

Means is provided for automatically returning the ejector 11 to its initial or retracted position at the completion of the ejecting operation or stroke. This means may include a rod or arm 51 secured to the under side of the ejector member 41. The arm 51 projects from one end of the member 41. An extensible spring 52 has one end connected with the arm 51. The other end of the spring 52 is secured to a clip 53 on the bottom 16 of the cabinet 10. The spring 52 is under tension and when the ejector 11 is moved forwardly the spring is extended or put under increased tension. The return spring 52 normally retains the ejector 11 in the fully retracted position and is operable to rapidly move or swing the ejector rearwardly when the ejecting operation is completed.

The means 12 for operating the ejector 11 is a manually operable means that swings the ejector 11 forwardly to project the front fold 33 of the lowermost towel T from the opening 21 as described above. The means 12 is preferably a simple easily operated lever means. In practice the means 12 includes a lever 54. A bearing 55 is secured in an opening in the lever 54 and mounts the lever on the shaft 43 for free pivotal movement. The lever 54 is provided adjacent one end of the ejector 11 and is spaced from the adjacent shaft bearing 44 by a spacer 56. The forward portion or the arm of the lever 54 freely passes through a slot 57 in the wall part 19 to project forwardly from the cabinet below the wall 20. The projecting portion of the lever 54 curves upwardly and outwardly. A suitable operating button 58 is secured to the upper or outer end of the lever 54 to facilitate the operation of the lever. It is a feature of the invention that the button 58 is positioned to be wiped and dried by the towels T as they are withdrawn from the cabinet 10. When the lever 54 is in its normal unactuated position the upper surface of the button 58 is immediately adjacent the lower wall of the discharge opening 21 and the surface of the button is sloped and curved to be engaged by the towels as they are pulled from the cabinet 10. Fig. 7 of the drawings illustrates the manner in

which a towel T wipes the button 58 clean and dry.

The inner part or arm of the operating lever 54 is freely received in a corner notch 59 in the ejector member 41 to be free and independent of the ejector 11. A laterally projecting lug 60 is provided on the inner arm of the lever 54. The lug 60 is adapted to cooperate with the under side of the ejector member 41 to transmit movement from the lever 54 to the ejector 11. The lug 60 has a downwardly projecting portion carrying a bumper 61 of rubber, or the like. The bumper 61 is adapted to engage the bottom 16 of the cabinet 10 to limit the return movement of the lever 54. The ejector member 41 is adapted to engage against the lug 60 to limit the return movement of the ejector 11. When the operating button 58 is depressed the lever 54 is pivoted and the lug 60 engaging against the ejector member 41 transmits movement from the lever to the ejector 11 so that the ejector is swung or pivoted forwardly to eject the fold 33 of the lowermost towel T as above described. An outwardly projecting lateral lug 62 is provided on the inner arm of the operating lever 54 and carries a bumper 63 of rubber, or the like. The bumper 63 is adapted to engage against the inner surface of the wall part 19 to limit the ejecting movements of the lever 54 and the ejector 11. The invention includes means for automatically returning the operating lever 54 to its normal initial position. A pin 64 projects from the inner arm of the lever 54 and an extensible spring 65 has one end secured to the pin 64. The spring 65 extends rearwardly from the lever 54 and has its rear end secured to a clip 66 on the cabinet bottom 16. The spring 65 is under tension and is extended or elongated when the lever 54 is actuated. Upon the release of the actuating pressure on the lever button 58 the spring 65 serves to quickly return the lever 54 to its normal position, thus bringing the button 58 to the position where it will be wiped and dried by the towel T being withdrawn from the cabinet 10. It is important to note that the operating lever 54 of the means 12 is pivotally supported independently of the ejector 11 and returns to its normal position independently of the ejector. Upon the return of the lever 54 to its normal position the lug 60 moves rearwardly away from the ejector member 41 so that the lever is entirely clear and free of the ejector. In the event that the operator of the cabinet manually returns the lever 54 this action can in no way affect the ejector 11.

The control or time delay means 13 retards or delays the return of the ejector 11 to its normal position following each ejecting operation. The ejector 11 is incapable of engaging a towel fold 33 to eject the same through the opening 21 until and unless the ejector is in its fully retracted initial position at the start of the ejecting stroke. The time delay means 13 delaying or retarding the return of the ejector 11 to its normal position therefore makes it impossible to successfully operate the device for a fixed and selected period following the ejection and withdrawal of a towel. It is an important feature of the invention that the means 13 allows free, substantially unrestrained return movement of the ejector 11 during the first phase of its return stroke and serves to retard or delay the return movement during the second and final phase of its return stroke. This feature assures the immediate withdrawal of the ejector member 42 and the roller 49 from the opening 21 to positions within the cabinet 10

where they cannot be manually grasped or tampered with.

In accordance with the broader aspects of the invention the time delay means 13 may be varied considerably in character, it being apparent that movement retarding or delaying means of various natures may be utilized to delay the final return motion of the ejector 11. In the illustrative form of the invention shown in the drawings the means 13 is in the nature of a cylinder and piston means or a dashpot means. As illustrated, the means 13 comprises two elements, namely, a cylinder 67 and a plunger 68 operable in the cylinder. One of the elements 67 or 68 is connected with the ejector 11 to be moved thereby and the other element 67 or 68 is connected with the cabinet 10 or a suitable stationary object. In the arrangement shown in the drawings the cylinder 67 is pivotally mounted in the cabinet 10 and the piston 68 is connected with the ejector 11.

The inner or rear end of the cylinder 67 is closed by a head 69 and an angular bracket 70 is secured to the head 69. In the preferred construction the means 13 is adjustable or regulable so that it may retard or delay the completion of the return stroke of the ejector 11 for any selected period. The cylinder 67 is adjustably or shiftably mounted to provide for this regulation of the means 13. A vertical slot 71 is provided in the rear portion of one of the mounting plates 37. The slot 71 may also pass through a reinforcing strip 72 on the plate 37. A pin or bolt 73 passes through the slot 71 and through an opening in the bracket 70. The bolt 73 is shiftable vertically in the slot 71. A slotted nut 74 is provided on the inner end of the bolt 73 to retain the bracket 70 on the bolt. The bracket 70 is freely turnable on the bolt 73 to permit pivoting of the cylinder 67 during operation of the ejector 11. When the nut 74 is loosened the bolt 73 may be shifted vertically in the slot 71 to change the angle of the cylinder 67 and therefore change the stroke of the means 13 as will be more fully described.

The piston 68 may be in the nature of a rod provided at its rear end with a head or cup leather 75 operable in the cylinder 67. The rod or piston 68 passes through and is guided by a suitable head 76 on the forward end of the cylinder 67. The cup leather 75 is arranged to have its concave side facing rearwardly to expand against the wall of the cylinder 67 when the piston moves inwardly. The forward end of the piston 68 has an opening 77 turnably receiving a reduced end 55 part of the arm 51 to connect the piston with the ejector 11. It will be seen that during the return movement of the ejector 11 the piston 68 moves rearwardly in the cylinder 67. The return spring 52 is preferably of substantial strength to return the ejector 11 quite rapidly during the first portion of its return stroke. As the piston 68 moves rearwardly in the cylinder 67 the air trapped behind the cup leather 75 is compressed and offers resistance to inward movement of the piston 68. The air compressed in the cylinder 67 expands the cup leather 75 into tighter engagement with the wall of the cylinder 67. Throughout the final phase of return movement of the ejector 11 the cup leather 75 seals with the wall of the cylinder 67 with only slight leakage so that the return motion of the ejector is materially retarded and delayed. The cup leather 75 is such that the compressed air trapped behind it slowly leaks past the cup leather assuring the

complete return of the ejector 11 to its initial retracted position under the action of the return spring 52. It will be seen how the spring 52 and the time delay means 13 may be balanced or related to provide for the proper or desired action of the ejector 11. During the active or ejecting stroke of the ejector 11 the cup leather 75 contracts to permit free movement of the piston 68 and the ejector. By adjusting the rear end 10 of the cylinder 67 vertically in the manner described above the stroke of the piston 68 in the cylinder may be varied so that the means 13 operates to delay the return stroke of the ejector 11 for any given or selected period.

In the use or operation of the dispensing device described above the cabinet 10 is mounted on a suitable support and is supplied with a stack of towels T. The front 18 may be easily swung to its down or open position to permit the ready insertion of the towels T in the cabinet. When a user desires to obtain a towel T he merely presses down on the button 58 to pivot the lever 54. The lug 60 transmits movement from the lever 54 to the ejector 11 and the ejector swings forwardly. During the forward movement of the ejector 11 the roller 49 and the member 42 enter between the fold 33 and the body of the lowermost towel T. The forwardly moving ejector member 42 bears on and is guided by the roller 31 and moves forwardly toward and then through the opening 21. The member 42 and the roller 49 bend or project the fold 33 down and out through the opening 21 to a position such as shown in Fig. 6. The forward portion of the lowermost towel T is confined against the shelf 27 by the weight of the other towels T and the fold 33 is confined between the member 42 and the lower wall of the opening 21. The fold 33 is thus held wrapped or trained about the roller 49 and the member 42 when projected through the opening 21.

The user may conveniently grasp the projected towel fold 33 or double thickness portion of the towel and pull forwardly on the same to remove the lowermost towel T from the cabinet 10 without danger of parting or tearing the towel. The projected portion of the towel T being of double thickness resists tearing and may absorb substantial moisture without being weakened. When the towel T is pulled forwardly through the opening 21 its forward portion is first freed from the shelf 27 and the body of the towel freely moves across the rotatable roller 31. The rear fold 34 freely slides off the shelf 29 and passes under the stationary roller 31. As the towel T moves forwardly the rear fold 34 straightens out or unfolds and then passes over the roller 31. Thus the major portion of the towel T is unfolded for immediate use.

Immediately upon the relaxation of the actuation pressure on the button 58 the spring 65 pivots the lever 54 to restore it to its normal position. In practice the lever 54 is returned to its normal position while the towel T is being withdrawn from the cabinet 10 and the outwardly moving towel wipes across the top of the button 58 to clean and dry the same. The button 58 is thus left in a dry sanitary condition following each operation of the device. The operating lever 54 returns to its initial position independently of the ejector 11.

When the lever 54 is released at the completion of the ejection stroke the spring 52 serves to swing or pivot the ejector 11 toward its normal retracted position. The spring 52 operates to

quickly move the ejector 11 rearwardly during the first phase of its return stroke to retract the roller 49 and the member 42 within the cabinet 10. As the ejector 11 moves to its normal position the member 42 may ride on the roller 31 and the roller 49 may lightly engage against the lowermost towel T but does not in any way disturb the towel. As above described the air trapped behind the cup leather 75 is compressed as the piston 68 moves rearwardly and throughout the final portion of the ejector's return stroke the compressed air in the cylinder 67 holds the cup leather 75 in tight sealing engagement with the wall of the cylinder 67. The air trapped behind the cup leather 75 retards the rearward motion of the piston 68 and the ejector 11. This retardation of the return stroke of the ejector 11 continues to the end of the return stroke. The means 13 operating in this manner delays the return of the ejector 11 to its normal position for a substantial given duration of time. As described above the ejector 11 is not conditioned to eject a second towel T until it has reached its fully retracted position and as it does not reach this position until the lapse of a given time, allowing a preceding operation, the device cannot be operated in rapid succession to obtain a number of towels T.

An attempt to obtain a second towel T immediately following the removal of one towel from the cabinet 10 merely returns the ejector 11 to its projected position without in any way affecting the lowermost towel T in the cabinet. When the ejector 11 is moved forwardly by an operation of the lever 54 prior to the return of the ejector to its fully retracted position the roller 49 and the member 42 move forwardly without engaging under the fold 33 on the lowermost towel T. Accordingly, the forwardly moving ejector 11 does not project the fold 33 from the opening 21 for engagement by the user. The ejector 11 must be restored to its fully retracted position by the spring 52 before the device may be operated to obtain another towel T.

The towels T are stacked and supported in a cabinet 10 in such a manner that they cannot be engaged or tampered with. The lowermost towel T is above the opening 21 and the edge of its fold 33 is a substantial distance inwardly from the opening and cannot be tampered with. The dispensing device may be repeatedly operated as described above until the supply of towels T has been exhausted.

Fig. 8 of the drawings illustrates an alternative form of the invention in which the operating lever 54 is permanently connected with the ejector 11. The lever 54 and the ejector 11 may be connected in any desired manner. In the construction illustrated the lug 60 on the lever 54 is secured to the ejector member 41 by rivets 80. The connection between the lever 54 and the ejector 11 is such that these two elements operate simultaneously during both the ejection stroke and the return stroke of the ejector. The operation of the construction illustrated in Fig. 8 is the same as that of the previously described form of the invention except that the lever 54 returns to its normal position simultaneously with the return of the ejector 11. If desired or if necessary the lever-returning spring 65 may be dispensed with and the spring 52 may be utilized to return both the ejector 11 and the member 54.

Having described only typical preferred forms and applications of my invention, I do not wish to be limited or restricted to the specific details

herein set forth, but wish to reserve to myself any variations or modifications that may appear to those skilled in the art or fall within the scope of the following claims.

Having described my invention, I claim:

1. A device for dispensing articles of sheet material comprising a cabinet for housing said articles and having a discharge opening, two elements, one an ejector for ejecting said articles through the opening, the other a manual operating member for operating the ejector, means for restoring the ejector to its initial position to condition it for subsequent operation, means for restoring the operating member to its initial position, and a time delay mechanism for retarding the restoration of one of said elements.

2. A device for dispensing articles of sheet material including a cabinet for said articles having a discharge opening, a movable ejector in the cabinet operable to eject the articles through the opening, manual means for operating the ejector, means for returning the ejector to position for a subsequent operation, and a time delay mechanism for delaying the return of the ejector to prevent the immediate successive ejection of the articles.

3. A device for dispensing articles of sheet material including a cabinet for said articles having a discharge opening, a movable ejector in the cabinet operable to eject the articles through the opening, a manually operated member for moving the ejector to eject the articles through the opening, the ejector and the said member being free for separate movement to their normal positions, means for restoring the ejector to its normal position, means for restoring the said member to its normal position, and a time delay mechanism for retarding the restoration of the ejector.

4. A device for dispensing sheet articles each having a fold, comprising a cabinet for containing the articles and having an opening, a shiftable ejector in the cabinet shiftable from its normal position to move the fold of an article through said opening to expose an article portion of double-thickness for engagement by the user, means for shifting the ejector, including a manually engageable operating member, means for returning the ejector to its normal position, the ejector being incapable of engaging an article to move the same except when in the said normal position, and a time delay mechanism for delaying the return of the ejector.

5. A device for dispensing sheet articles each having a fold, comprising a cabinet for containing the articles and having an opening, a shiftable ejector in the cabinet shiftable from its normal position to move the fold of an article through said opening for engagement by the user, means for shifting the ejector including a manually engageable operating member, means for returning the ejector to its normal position, the ejector being incapable of engaging the fold of an article to move the same except when in the said normal position, and a time delay mechanism for governing the return of the ejector only during the last portion of its return stroke.

6. A device for dispensing sheet articles each having a fold, comprising a cabinet for containing the articles and having an opening, a shiftable ejector in the cabinet shiftable from its normal position to move the fold of an article through said opening for engagement by the

user, means for operating the ejector to move the fold of the article through said opening including a manually operable member supported for movement separately from the ejector, and cooperable parts on the ejector and member for transmitting movement from the member to the ejector upon manual actuation of the member in one direction, spring means for moving the member in the other direction to return the same, spring means for returning the ejector, and a time delay device for retarding the action of the last named spring means.

7. A device for dispensing sheet articles each having a fold, comprising a cabinet for containing and completely housing the articles and having an opening, a shiftable ejector in the cabinet shiftable from its normal position to move the fold of an article through said opening for engagement by the user, means for moving the ejector in a direction to move the fold through the opening for engagement by the user including a lever at the exterior of the housing and mounted at a point on the housing remote from the opening, and a manually engageable part on the lever positioned at the exterior of the cabinet normally adjacent the opening to be wiped by the sheet article as it is withdrawn from the cabinet, and means for returning the lever to its normal position following the operation.

8. A device for dispensing sheet articles having folds comprising a cabinet for containing the articles and having an opening, a swingable articulated ejector in the cabinet comprising an inner element, and a sheet engaging element movably connected with the inner element, means for swinging the ejector, and means for moving the said sheet engaging element of the articulated ejector relative to the said inner ejector element to engage the ejector in the fold of an article and project the fold through the opening.

9. A device for dispensing sheet articles having folds comprising a cabinet for the articles having an opening, means for supporting the articles in stacked relation with the fold of the lowermost article free but inaccessible from the exterior of the cabinet, a pivotable ejector in the cabinet including an inner member and an outer member pivoted to the inner member and spring-urged to bear toward the articles, means for pivoting the ejector toward the opening, means engaging the outer member during the pivoting of the ejector to cause said outer member to engage in the fold of the lowermost article and direct it out through said opening for withdrawal by the user, and means for returning the ejector to its normal position.

10. A device for dispensing sheet articles having folds comprising a cabinet for the articles having an opening, means for supporting the articles in stacked relation with the fold of the lowermost article free, a shiftable ejector in the cabinet shiftable from its normal position to engage in the fold of the lowermost article and move the fold through the opening for grasping by the user, means for shifting the ejector including a manual operating part secured to the ejector, means for returning the ejector to its normal position, and a dashpot mechanism for retarding the return of the ejector, the ejector being unable to engage in the fold of the lowermost article except when shifted from its said normal position.

LEO M. HARVEY.
